Claims priority, application France Mar. 24, 1966

Term of patent 3½ years

(Cl. D87—1)

FIG. 1

FIG. 2

FIG. 3

FIG. 1 is a perspective view of the rear and side of a cargo shipping container showing my new design;

FIG. 2 is a perspective view of the front and other side thereof; and

FIG. 3 is a front perspective view thereof showing the doors in open condition.

The top is corrugated in the same manner as are the sides.

The characteristic feature of my design resides in the combination on the cargo shipping container disclosed of the uniform square corrugated sides in conjunction with jamb and linto fork-lift reinforcements on two sides.

I claim:

The ornamental design for a cargo shipping container, as shown and described.
